UNITED STATES PATENT OFFICE

BURTNETT MCINTOSH, OF FLORAL PARK, NEW YORK, ASSIGNOR TO FRANK A. HALL & SONS, OF NEW YORK, N. Y.

BED

Application filed September 10, 1927. Serial No. 218,620.

This invention relates to beds, and particularly to beds of the type having enclosed sides.

The invention aims to improve the frame construction of such beds in order to render them more sturdy and rigid while preserving an economical construction.

The invention includes an arrangement whereby one of the sides of the bed may be expeditiously lowered on sliding rails, and embraces also a foot operated latch for maintaining the sliding section in raised position.

While a preferred embodiment has been disclosed for purposes of illustration, it should be understood that various changes may be made in the structure without departing from the spirit and scope of the invention as hereinafter set forth and claimed.

In the drawings;

Fig. 1 is a side elevation of a bed embodying the invention.

Fig. 2 is an end elevation of the bed.

Fig. 3 is a side elevation of the rear part of the bed.

Fig. 4 is an enlarged sectional detail.

Fig. 5 is a view similar to Fig. 4 but showing the parts in a different position.

Fig. 6 is a section on line 6—6 of Fig. 2.

Fig. 7 is an enlarged perspective of a part 30 of the latch.

Fig. 8 is an enlarged perspective of part of the latch-operating mechanism.

Fig. 9 is a plan of the hook-carrying end piece.

Referring to the drawings more specifically, the bed comprises a spring frame 10 supported by a head section 11 and a foot section 12. The spring frame is formed of side rails 13 of angle iron, which are joined at their ends by rails 14. The side rails carry at each extremity a cast hook-piece 15 of the shape illustrated in Fig. 9. Each of these hook-pieces is formed with a hook 16 which is adapted to project beyond the end of the spring frame and engage over one of the transverse rods 17 carried by the head and foot sections. The hook pieces are also provided with transverse lugs 18 at their upper and lower edges, these lugs being adapted to engage the corner posts

19 of the head and foot sections to brace these sections against lateral movement.

When the bed is to be used as a crib it is provided with a vertically movable front section 20 as shown in Fig. 1. The top and bottom rails of this front section have their ends formed with ears 21 which slide over guide rods 22 attached to the corner posts 19. A latch mechanism is provided for holding the front section in raised position, and the latch is connected with a foot lever 23 in such a manner that operation of the foot lever will permit the front section to be lowered.

The latch mechanism will now be described. Referring to Fig. 9 it will be noticed that each end piece 15 is formed with an inverted T slot 24 near its lower edge, leaving a round bar 25 below the slot. The latch bar 26, which is of the shape shown in Fig. 7, has its lower end 27 curved to fit around the bar 25 and carries a lug 28 adapted to extend through the stem of the T slot 24. A concave groove 29, formed in the forward face of the latch bar, fits around the guide rod 22 when the parts are in the latched position of Fig. 4. One of the ears 21 then fits over the top of the latch bar and due to the shape and angular position of the latch bar, the front section is held against downward movement. A coiled spring 30 fits over the lug 28 and has one end pressing against the hook-piece 15 while its other end is anchored in a hole 31 formed in lug 28. Due to this mounting the spring 30 normally tends to press the latch bar away from guide rod 22 to the unlatched position of Fig. 5.

The latch bars 26 are moved to latching position by the following mechanism: The operating members 32, shown in Fig. 8, comprise cruciform shanks 33 which merge into flat portions 34 carrying end segments 35. These operating members are pivoted to the end rails by bolts 36 passing through apertures 37 in segments 35, and their shanks are connected by a square tube 38 to cause them to rotate in unison. A tension spring 39 has one end hooked in a hole 40 formed near the upper edge of flat portion 34, the opposite end of the spring being suitably attached to the end rail 14. This spring normally tends to turn the operating member in a counter clockwise di-

rection so that the lower part of the portion 34 engages the lug 28 to press latch bar 26 toward the rod 22 as in Fig. 4.

The upper end of foot lever 23 is pivoted to the segment 35 at 41, so that downward pressure on the foot lever will rock the operating members in a clockwise direction to the position of Fig. 5, permitting spring 30 to move the latch bar away from the guide rod when the front section has been raised to disengage ear 21 from the upper end of the latch bar.

The rear side of the bed is closed by a section 42 which may be removed when desired, but is not adapted to be lowered in a manner similar to the front section. The top rail 43 of this rear section carries at each end a depending forked wedge lug 44 which fits over a pin 45 mounted on the end frame. The end uprights 46 of the rear section project through holes formed in the upper surface of hook piece 15, thereby preventing lateral movement of the rear section.

The movable front section is normally in the raised position shown in Fig. 1, and is held in that position by the latch bars 26 in the manner indicated in Fig. 4. When it is desired to lower the front section it is first slightly raised to disengage ears 21 from the upper ends of the latch bars, and the foot lever 23 is then depressed to rock the operating members to the position of Fig. 5 and permit the spring 30 to move the latch bar to the unlatched position. The front section may now be lowered, and springs 47 coiled about the lower ends of guide rods 22 will softly cushion its descent.

It will be clear from the above disclosure that applicant's device provides a perfected safety latch for the movable section since it is impossible for the occupant of the bed to lower the movable section, and it is also impossible to lower the front by accidental tripping of the foot lever. To accomplish this action it is necessary to first raise the front section and hold it elevated while the foot lever is depressed to release the latch.

I claim:

1. A bed comprising frame members, end sections, vertical guide rails carried by the end sections, a front section having ears riding along the guide rails, a latch bar pivotally mounted on one of the frame members and adapted to contact with a guide rail under one of the aforesaid ears to maintain the front section in elevated position, a spring normally biasing the latch bar away from the guide rail, and a foot-controlled operating member adapted to control movements of the latch bar.

2. A bed comprising frame members, end sections, vertical guide rails carried by the end sections, a front section having ears riding along the guide rails, a latch bar pivotally mounted on one of the frame members and adapted to contact with a guide rod and to

extend into one of the aforesaid ears to maintain the front section in elevated position, a spring normally biasing the latch bar away from the guide rail, a pivoted operating member for moving the latch bar toward the guide rail, a spring normally biasing the operating member toward the latch bar, and a foot lever connected to the operating member for moving the operating member away from the latch bar.

3. A bed comprising frame members, end sections, vertical guide rails carried by the end sections, a front section having ears riding along the guide rails, a latch engaging an ear of the front section for maintaining said section in elevated position, a lever for operating the latch, the engaged front section ear normally fitting over the latch to prevent unlatching until after the front section has been raised.

4. A bed comprising frame members, end sections, vertical guide rails carried by the end sections, a front section having ears riding along the guide rails, a latch bar pivotally mounted on one of the frame members and adapted to contact with the guide rail under one of the aforesaid ears to maintain the front section in elevated position, said engaged ear normally engaging around the latch to prevent releasing movement of the latch until said front section is raised, a spring normally biasing the latch bar away from the guide rail, and a foot controlled operating member adapted to control movement of the latch bar.

5. A bed including frame members and end sections, vertical guide rails carried by said end sections, a front section having ears riding along the guide rails, a latch bar pivotally mounted on one of the frame members and adapted to contact with a guide rail below one of said ears, an arm projecting laterally from the latch bar, an operating member pivoted to one of the frame members and having a shank portion engaging beneath said arm to tilt the latch into ear engaging position, a spring urging said latch out of ear engaging position, and a pedal having operative connection with the operating member to effect pivotal movement thereof.

In testimony whereof I affix my signature.

BURTNETT McINTOSH.
